UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

METHOD OF AND APPARATUS FOR SCREENING PAPER STOCK.

Application filed November 21, 1919. Serial No. 339,562.

To all whom it may concern:

Be it known that I, ANTON J. HAUG, a citizen of the United States, and resident of Nashua, county of Hillsborough, and 5 State of New Hampshire, have invented an Improvement in Methods of and Apparatus for Screening Paper Stock, of which the following description, in connection with the accompanying drawings, is a specification, like characters on the drawings representing like parts.

This invention relates to paper-making machines and more particularly, though not necessarily, to methods of and apparatus for 15 screening paper stock. The invention will be best understood by reference to the following description when taken in connection with the accompanying illustration of one specific embodiment thereof, while 20 its scope will be more particularly pointed out in the appended claims.

In the drawings:—

Figure 1 is a central, longitudinal, sectional elevation of the inlet end of a screen 25 embodying one form of the invention;

Fig. 2 is a similar view showing the opposite or outlet end of the screen;

Fig. 3 is a transverse, sectional elevation taken on the line 3—3 in Fig. 1, looking in the direction of the arrow or toward 30 the inlet end;

Fig. 3^a is a detail in section on the line 3^a—3^a in Fig. 2;

Fig. 3^b is a similar section on the line 3^b—3^b in Fig. 2;

Fig. 4 is a plan view of the devices contained within the screen drum for advancing the unscreened stock step by step; and

Fig. 5 is a plan view in section, taken 40 on the line 5—5 in Fig. 3, showing the separated feed passages for the stock.

Referring to the drawings and to the embodiment of the invention therein submitted for illustrative purposes, I have 45 shown the same as embodied in a screening apparatus for paper stock, the principal screening member of which is in the form of a screen drum. While the latter may be of any desired shape and may be either 50 rotatable or fixed, herein the same is rotatably mounted and polygonal in shape, the surface of the drum being formed by a series of flat, rectangular, perforated screen plates 10, herein eight in number, carried

by the end plates 11 and 12, the latter being octagonal in outline and secured to or fashioned integrally with the hollow journal members 13 and 14 respectively.

The entire drum is enclosed within a fixed casing or chamber having the encircling walls 15 secured to the opposite end frame members 16 and 17 respectively, the casing 15 at its bottom communicating with a suitable outlet passage 18 (Fig. 3) through which the screened stock, which passes through the screen drum from the interior to the exterior thereof, may escape and be conducted to any suitable point. The outlet for the screened stock is herein shown as provided with a weir-like plate 19 over 70 which the stock flows and the height of which controls the level of the stock within the casing. The plate 19 is held at opposite ends between guides 20 and 21 and may be replaced by a plate of greater or lesser 75 height to vary the stock level in the casing.

The casing and the end plate 16 rest upon any suitable support devices, such as the supporting feet 22, and provide a suitable journaled support for the rotary screen 80 drum, the same being herein in the form of a plurality of roller supports 23 at each end, upon which rollers the journal members 13 and 14 turn, rotation being imparted to the drum by any suitable means 85 such as the driving pulley 24 secured to the journal member 13.

In the described embodiment of the invention, the stock to be screened is delivered to the interior of the screen drum at one 90 end thereof, preferably through a continuous supply; and as the drum is rotated the stock is screened and the unscreened residue lifted and dropped. The unscreened residue, having been first preferably thinned or 95 diluted, is conducted by suitable feeding means which again deliver it to the drum but at an advanced point in its length so that substantially the same screening, lifting and dropping operation may be repeated. This is continued any desired 100 number of times until the final unscreened residue is delivered to the tailings outlet of the machine.

Referring first to the devices for delivering the entering stock to the interior of the drum and for advancing the enclosed residue step by step through the drum, while 105

such devices may be variously constructed and may be either movable or stationary, herein they are contained in a fixed, trough-like structure which passes through the drum from end to end and is provided with suitably arranged passages to direct the flow of the stock in the proper directions. This repository for the stock is supported on a frame extending through the machine from end to end and consisting of the channel irons 30 and 31 with the underlying connecting plate 32, the frame being supported at the inlet end by the bracket 33 secured to the adjacent supporting feet 22 and, at the outlet end, to brackets 34 which extend outwardly and rearwardly from the supporting feet 22 and end plate 17. This channel like frame forms a support for the stock repository and feeding member which herein is in the form of a single casting 40 bolted to the frame and provided with the necessary stock feeding passages.

At the inlet end of the machine this casting has a closed inlet passage 41 which extends through the inlet end of the machine where it communicates with the inlet chamber 42 and the inlet opening 43, the latter being formed in the casting 44 which is secured to the projecting end of the casting 40. The inlet passage 41 has a channel-shaped depression 45 and the inlet chamber 42 a corresponding depression, which depressions form a sand trap or settling chamber adapted to receive deposits of sand or other foreign matter which may settle or gravitate out of the stock as the latter enters the inlet chamber and affords passage to the screen drum. The end of the settling chamber is closed by a movable closure 46 through which the chamber may be cleaned from time to time as required.

The stock as it passes through the inlet chamber 41 flows over the horizontal wall 47 of the casting 40 until it encounters the diagonal partition wall 48 by which it is prevented from further advance and diverted against the overflow plate 49 (Figs. 3 and 5), the latter being of lesser height than the partition wall 48 and arranged longitudinally the drum at one side of the axis thereof and preferably on the descending side thereof. The stock passing over the overflow plate 49 passes down the surface of the inclined discharge plate 50 and is thereby delivered to the descending side of the drum, being preferably delivered thereto within certain longitudinal limits which are prescribed by the upright partition plates 51 and 52 on the discharge plate, the plate 52 coinciding with or forming a continuation of the partition plate 48.

The stock which is thus delivered to the drum, after being screened and lifted (as will be more fully described) is dropped from the ascending side of the drum at the

opposite side of the axis thereof where it again falls upon the flat plate 47 which at the ascending side of the drum is preferably inclined upwardly at 53 (Fig. 3) so as to catch the stock as it is dropped and assist in draining it toward the opposite or descending side of the drum.

The delivery of the screened residue to the plate 47 is also assisted by the deflector plate 60 which extends lengthwise the drum over the feed plate 47. The deflector plate 60 is fixedly secured to the ends of the feeding member and has its upper edge extending in close approximation to the rotating parts of the drum at one side of the axis thereof (the descending side) and is inclined downwardly toward the feed plate so that material which is carried up toward, to or past the center of the drum will drop on the deflecting plate and will gravitate upon the flat plate 47. This material, however, gravitates upon the plate 47 at the back of or on the opposite side of the partition wall 48, from which the stock enters the drum, so that it is separated from the unscreened stock entering through the inlet and is caused to flow through the diagonal passage formed between the partition wall 48 and a similar but more advanced partition wall 61 to a second overflow plate 62 on the descending side of the drum but at a more advanced point therein than the stock which is initially delivered thereto from the inlet passage.

The stock which is thus delivered to the drum past the overflow plate 62 for a second screening action is in turn screened, lifted and delivered to the feed plate 47 on the opposite side of the drum but between the partition wall 61 and a similar, more advanced partition wall 64, the two forming a second compartment or feed passage which directs the flow of the stock in the direction of the arrow shown (Fig. 5) to a third overflow plate 65 by which it is again delivered to the drum at a still more advanced point.

This operation may be repeated any desired number of times, the feeding apparatus illustrated in Figs. 4 and 5 being provided with means for rescreening the residue from the first screening operation five times, consecutive partition walls 66, 67 and 68 being provided and overflow plates 69 and 70, similar to those already described. Since the repeated rescreening results in a gradual withdrawal of portions of the stock and a step-by-step diminution in the amount rescreened at each time, preferably the successive passages in the feeding apparatus undergo a gradual diminution in available cross-sectional area, this being represented in Figs. 4 and 5 by a closer arrangement of the successive partitions for successive feeding passages.

Between each screening action and the next, the unscreened residue in each case is preferably thinned or diluted since the rejections from each screening operation are considerably thicker than the initial supply. Suitable thinning or diluting devices are therefore employed in the illustrated embodiment of the invention, the same herein consisting of a shower pipe 70 located in such position (and herein centrally above the axis of the drum and supported by the feeding plate casting) that it is adapted to discharge a shower of water into and over the gravitating residue and dilute or thin the same as it flows or moves toward the overflow plates 62 etc. This shower pipe extends through from the outlet end of the machine where it is supported by a bracket 71 carried by the supporting brackets 34 and has connection (not shown) to any suitable source of water supply.

Additional shower pipes may be employed if desired and herein two such pipes 72 and 73 are shown located one directly above the drum within the casing 15 and the other above the ascending side of the drum, so that the shower water is directed upon the stock-lifting surface of the drum and assists to free the slivers and fibres contained in the unscreened residue from the foraminous surface of the screen plates as well as assisting in diluting the stock.

After the last screening operation and after the unscreened residue or tailings have been delivered to the feed plate 47 between the partition walls 67 and 68, the residue passes over the edge 80 of the plate whereat it is delivered to the inclined plate 81 (see Figs. 2 and 5) and flows through the tailings outlet channel formed by the channel irons 30 and 31 and the underlying plate 32, being delivered from the end thereof into any suitable receptacle such as the tailings receiver 82.

Referring now to the construction of the screen drum, the latter, in the illustrated embodiment of the invention, is subdivided interiorly into separate stock-receiving compartments by means of partition walls which extend longitudinally the drum and are directed inwardly in a general radial direction for a short distance. Each screening plate herein carries three such compartments (Fig. 3) which are formed by the two partition walls 90 near the edge of the plate and the two intermediate partition walls 91. These partition walls are brought into successive registration with the discharge plate 50 as the drum rotates, so that the stock discharged by the discharge plate is delivered to the pockets and as the drum turns is more or less agitated as it is thrown from one corner of the compartment to the other. By means of the weir plate 19, a sufficient stock level may be

maintained in the casing to compel the plates 10 to dip beneath the surface of the same so that the water, forced back and forth through the perforations of the plates as the latter are submerged, also assists through a washing, drainage and suction action, in further screening the stock contained in the screening compartments of the drum. As the drum continues to turn, the partition walls 90 and 91 serve as lifting blades which retain the unscreened residue until it is brought within the influence of the shower pipes 73 and 72 and is raised to a sufficient elevation to insure its delivery to the feed plate 47.

In the described embodiment of the invention, also, the screen drum is further subdivided longitudinally into separate screening compartments by a series of circumferential, ring-like plates 92—92, these ring-like plates constituting partition walls which are located to coincide or register with the partition walls 51, 52, etc. which control the successive deliveries of stock to the successive portions of the drum, and also to register or coincide with the successive partition walls 48, 61, etc. on the feed plate and which confine the unscreened residue as it is delivered thereto by the drum to such a path as insures its redelivery to the drum in the next succeeding circumferential compartment thereof. These circumferential partition walls therefore subdivide the drum into compartments corresponding to the successive feed passages of the feeding plate so that at each successive rescreening the unscreened stock is confined to a part of the drum where it is separated from portions of the stock which have been subjected to a greater or lesser number of screenings, thus insuring that all stock delivered to the drum will be subjected to substantially the same screening effect before being rejected at the tailings outlet.

As a simple and efficient means of constructing the screen drum, the perforated plates 10 are carried each by a grid-like support which extends from one end plate 11 to the opposite end plate 12, the opposite ends of each plate being fastened as by the bolts 100 (Fig. 1) to the end ring. Each grid-like support is composed of the longitudinal partition walls 90 and 91 and the segmental, circumferential partition walls 92. When the several supports are bolted in position to the end plates, they form a skeleton support for the perforated plates 10 with the corresponding circumferential partition walls in registration so as to constitute the circumferential partitions 92.

The partition walls 90 at the edge of each grid-like support are considerably thickened at the base or where the plate 10 is adapted to rest thereagainst so that when

the grids are assembled the two partition walls of adjoining supports constitute a single lifting blade which tapers or converges inwardly so that there is not only provided a substantial support for the edge of the plate but the corner, which would otherwise exist at one side of each compartment adjoining each vertex of the polygonal drum, is rounded or filled out, thus avoiding any space which might catch or retain stock. This construction also provides lifting compartments the bottoms of which are entirely covered by foraminous or perforated portions of the plates 10.

If desired, at suitable points longitudinally in the adjacent partition walls 90 the adjoining supports may be bolted together by means of bolts 101 (see Fig. 2 and the section Fig. 3^b). To secure the plates to the drum, means are herein employed which effectively hold them in position and at the same time assist in drawing the thin plates flat upon the support. For this purpose, herein the adjacent edges of adjoining plates are engaged by the beveled or wedge-shaped strips 102, the face of each strip being engaged at intervals by beveled face clamps, each clamp consisting of a pair of clamping members 103 which are drawn together by the bolt 104, the bolt being anchored or held against a radial outward movement by a strap 105 which is secured to a pin 106 arranged transversely in the underlying and adjoining partition walls 90. As the bolt 104 is tightened, the clamps are drawn together and this in turn binds the edges of the plates 10 tightly to the grid-like supports and tends to stretch them flat thereon. At opposite ends each plate is similarly clamped to the end plates 11 and 12 respectively by the wedge-shaped strips 107, clamps 108 and clamping bolts 109 (Fig. 1).

The drum is thus actually made up of segmental units, each unit serving as the sole support for the plate corresponding to that segment. Therefore any one plate or any one segment may be removed and replaced without dismantling the drum.

Preferably, at each opposite end of the casing removable closures are provided such as the closures 110 and 111 through which an inspection of the interior of the apparatus may be had at any time and through which any trouble may be corrected which arises, such for example as a clogging of the feeding passages or improperly working shower pipes. The end plates 11 and 12 are provided with suitable openings 112 through which inspection of and access to the interior of the drum can readily be had through the respective inspection openings. The feeding passages of the feed plate being opened and exposed, any tendency to clog or obstruct the feed is reduced to a minimum and, if or when it occurs, can be

easily ascertained through the inspection openings referred to.

To provide against an accidental stoppage of the drum rotation, as for example by the slipping of the drive belt, an overflow may be provided which will take care of stock in the drum likely to accumulate before the feed of the stock supply can be shut off. For this purpose the end plate 17 has an overflow opening 113 from which there projects an overflow spout 114 through which stock may escape over the weir plate 115, in case the drum, through any such accidental stoppage, becomes filled with stock to a height sufficient to permit it to escape through the openings 112 in the end plate 12.

In order to better adapt the tailings to some subsequent process of refinement or for some other reason, it may be desirable to thicken the consistency of the tailings by removing some of the moisture which they have when discharged. For this purpose I have shown the screen near its tailings outlet equipped with a drying device adapted to remove water from the tailings, such drying device herein consisting of the rotary, cylindrical, foraminous drying drum 126 which is secured to the end of the journal member 14 to turn therewith about the tailings outlet passage. If it is desired to thicken the tailings, a cover plate 121, which is normally used to cover an opening 122 in the bottom of the tailings passage, is removed so that the tailings are discharged through the opening 122 into the draining drum 120.

The latter is slightly flared or longitudinally tapered so that as the drum turns the tailings are slowly advanced toward the mouth thereof until discharged into the tailings receptacle 82. In the course of their advance through the drum, however, they are agitated more or less and rolled over and over as they are carried up the ascending side of the drum. This extracts more or less water from the stock, which water falls into the underlying chamber 123, escaping through the passages 124 which lead downwardly and inwardly through the end plate 17 into the screened stock chamber. The exposed portion of the tailings discharge passage and the draining drum 120 may be covered for protection by the removable, semi-cylindrical cover 130.

The delivery of the shower pipe 70, as well as that of the pipes 72 and 73, is confined to an area within the main casing 15, so that there is no further dilution of the tailings after they enter the draining drum 120.

While I have herein shown and described for purposes of illustration one specific embodiment of the invention, it is to be understood that the same is not limited to the details of construction herein shown or to the form or relative arrangement of parts,

but that extensive deviations may be made therefrom without departing from the spirit of the invention.

Claims:

5. 1. A screening apparatus for paper stock, the same having a rotary screen drum the interior of which is subdivided longitudinally into separate screening compartments whereby the stock delivered to the inlet end 70
 10 may be screened, lifted and dropped by the rotation of the drum, and stock-advancing means comprising a repository for the dropped stock with separate passages, one for each screening compartment, adapted to 75
 15 advance the residue from each screening operation and deliver it to the next or more advanced compartment of the drum, said passages at their receiving end registering with the delivery from one compartment and at 80
 20 their delivery end with the next adjacent compartment of the drum.
2. A screening apparatus for paper stock, the same having a rotary screen drum the interior of which is subdivided longitudinally by circumferential partition walls into separate screening compartments and is subdivided circumferentially by longitudinally arranged partition walls, whereby the stock delivered to the inlet end may be screened, 90
 25 lifted and dropped by the rotation of the drum, and advancing means comprising a repository for the dropped stock with separate passages, one for each screening compartment, and adapted to advance the 95
 30 residue from each screening operation and deliver it to the next, more advanced compartment of the drum, said passages registering at their receiving end with the delivery from one compartment and at their delivery end with the next adjacent compartment of the drum. 100
3. A screening apparatus for paper stock, the same having a rotary screen drum subdivided both circumferentially and longitudinally into screening compartments, said drum having an inlet at one end whereby stock may be delivered to the drum and an outlet at the opposite end whereby the tailings may be withdrawn therefrom, and 110
 45 means to receive the tailings emptied from each screening pocket as the same are lifted in the course of rotation of the drum and deliver the same to a screening compartment on the next or more advanced series for a repetition of the screening operation. 115
4. A screening apparatus for paper stock, the same having a rotary screen drum subdivided both circumferentially and longitudinally into screening compartments, said 120
 50 drum having an inlet at one end whereby stock may be delivered to the drum and an outlet at the opposite end whereby the tailings may be withdrawn therefrom, means to receive the tailings emptied from each screening pocket as the same are lifted in 125
 55
- the course of rotation of the drum and deliver the same to a screening compartment on the next or more advanced series for a repetition of the screening operation, and means for diluting the stock residue prior to 70
 60 each rescreening.
5. A screening apparatus having a rotary screen drum subdivided by circumferential partition walls into separate compartments lengthwise the drum, a stock repository device extending through the drum and presenting feeding passages adapted to receive stock from one compartment and advance it to the next, each of said passages having partition walls which coincide at their stock-receiving end with one compartment and at their delivery end with the circumferential partition walls of the next adjacent compartment. 80
6. A screening apparatus for paper stock, 85
 the same having a rotary screen drum the interior of which is subdivided by circumferential plates to present separate screening compartments, each compartment being also subdivided longitudinally by plates, 90
 to provide lifting blades for the separate compartments, said drum having an inlet through which stock to be screened may be delivered to a compartment near the inlet end and screened, lifted and dropped 95
 through the rotation of the drum, and stock-advancing and feeding means whereby the residue from each screening operation is advanced and delivered to a more advanced compartment in the drum for a repetition 100
 of the screening operation, the same comprising a repository member in the form of a plate having dividing walls presenting open passages adapted to conduct the deposited residue diagonally from the point 105
 deposited at one side of the drum axis to a more advanced point on the opposite side, the receiving end of the passages registering with the delivery of one compartment of the screen and the discharge registering with 110
 the next more advanced compartment.
7. A screening apparatus for paper stock, the same having a rotary screen drum by which the stock is screened, lifted and dropped, and stock-advancing or feeding means comprising a trough-like repository consisting of a plate with dividing walls to present uncovered passages adapted to conduct the deposited residue diagonally from a point on one side of the drum axis to a 115
 more advanced point on the opposite side and thereat deliver it again to the drum. 120
8. In a screening apparatus for paper stock, the combination with a screen drum adapted to screen, lift and discharge the unscreened residue through the rotation of the drum and means for delivering the unscreened residue from any screening operation again to the drum, the same having diagonally arranged feeding passages 125
 65 130

- 6 cated above the axis of the drum and terminating at an inclined discharge plate, the latter providing a path to the underlying drum.
- 5 9. In a screening apparatus for paper stock, the combination with a screen drum adapted to screen, lift and discharge the unscreened residue through the rotation of the drum and means for delivering the unscreened residue from any screening operation again to the drum, the same having diagonally arranged and open feeding passages located above the axis of the drum.
- 10 10. The combination with a rotary screen drum of means to deliver stock within said drum, the stock being screened and the residue lifted and dropped, and means to deliver the residue again to said drum, said means including a feeding plate with diagonally arranged uncovered feeding passages thereon.
- 15 11. An apparatus for screening paper stock having a rotary screen drum provided with interior lifting blades, said drum being adapted to screen the stock and lift and drop the unscreened residue, and means for advancing the unscreened residue within the drum, the same including a downwardly directed discharge plate adjacent the bottom of the drum with the end of which the lifting blades are adapted to register in succession as the drum rotates.
- 20 12. An apparatus for screening paper stock, the same having a rotary screen drum adapted to screen the stock, lift and drop the same, and means for advancing the stock within said drum, the same including a substantially flat plate provided with diagonally arranged feeding passages.
- 25 13. An apparatus for screening paper stock, the same having a rotary screen drum adapted to screen the stock, lift and drop the same, and means for advancing the stock within said drum, the same including a substantially flat plate provided with diagonally arranged feeding passages and an overflow wall for each passage.
- 30 14. An apparatus for screening paper stock, the same having a rotary screen drum adapted to screen the stock, lift and drop the same, and means for advancing the stock within said drum, the same including a substantially flat plate, an overflow wall and a downwardly directed discharge plate for conducting the unscreened residue to the descending side of the drum.
- 35 15. A screening apparatus including a rotary screen drum with circumferential partition compartments and stock-advancing means including delivery passages having partition walls confining the delivery thereof to a path coinciding with the circumferential compartments.
- 40 16. A rotary screen drum having a foraminous surface and subdivided into screen-
- ing compartments by longitudinal partitions, said compartments being further subdivided circumferentially.
- 45 17. In an apparatus for screening paper stock the combination with a screen drum having a polygonal cross-section, the interior being divided into screening compartments by longitudinal subdivisions and the compartments being subdivided into successive series by circumferentially arranged partitions, of stock advancing devices adapted to receive stock from one compartment and deliver it to a more advanced one.
- 50 18. In an apparatus for screening paper stock the combination with a screening drum having a foraminous surface and subdivided interiorly both circumferentially and longitudinally into separate screening compartments by unperforated partition walls, of stock advancing devices adapted to receive stock from one compartment and deliver it to a more advanced one.
- 55 19. In an apparatus for screening paper stock, the combination with a screening drum, polygonal in cross-section and presenting successive, flat, foraminous faces, each flat face being interiorly subdivided by longitudinal partition walls into separate screening compartments, of stock advancing devices adapted to receive stock from one compartment and deliver it to a more advanced one.
- 60 20. In an apparatus for screening paper stock, the combination with a screening drum having a polygonal cross-section and having one or more longitudinal partition walls between each vertex of the polygon to separate each flat face thereof interiorly into two or more screening compartments, of stock advancing devices adapted to receive stock from one compartment and deliver it to a more advanced one.
- 65 21. A screening drum polygonal in cross-section and separated interiorly and longitudinally into separate screening compartments and a partition member located at or near the junction of two adjacent flat faces and having partition walls which converge inwardly.
- 70 22. A screen drum having a polygonal cross-section separated interiorly into longitudinal screening compartments and a partition member between two adjacent compartments and located at the juncture of two adjacent faces of the drum, said partition member being thickened at the point nearest the drum face.
- 75 23. A rotary screen drum subdivided interiorly into separate screening pockets by longitudinal partition members, one of said partition members having partition walls which converge inwardly.
- 80 24. A polygonal screen drum having end supports, a foraminous wall for each flat face of the drum, a grid-like support for
- 85 90 95 100 105 110 115 120 125 130

each foraminous wall adapted to be fastened at opposite ends to the end supports and to present each a plurality of longitudinal walls adapted to constitute stock-lifting

5 blades and a plurality of transverse walls adapted to register in adjacent supports and when assembled to constitute interior circumferential partitions, the adjacent supports presenting longitudinal walls closely 10 adjacent one another and converging inwardly toward each other.

25. A screen drum having a polygonal cross-section, end supports and a foraminous wall for each flat face of the drum, a grid-like support adapted to be fastened at opposite ends of the end supports and presenting each a plurality of longitudinal walls adapted to constitute stock-lifting blades, the adjacent supports presenting longitudinal walls closely adjacent each other and converging inwardly and towards each other.

26. A rotary screen drum having a foraminous surface and composed of a plurality of 25 grid-like members secured at opposite ends to suitable end supports and serving as a support for the foraminous covering, said grid-like members presenting longitudinal partition walls adapted to serve as interior 30 stock-lifting blades for the drum.

27. A rotary screen drum comprising end supports, a foraminous covering and a support for the foraminous covering, the same including a plurality of separate supports 35 fastened at their opposite ends to the end supports and presenting longitudinal blade members adapted to subdivide the interior of the screen into separate screening compartments.

40 28. A rotary screen drum comprising end supports, a foraminous covering and a support for the foraminous covering, the same including a plurality of separate supports fastened at their opposite ends to the end 45 supports and presenting segmental, circumferentially arranged partition members.

29. In a screening apparatus, a rotary 50 screen drum having a polygonal cross-section with means for supplying stock to the interior of the drum, said drum being composed of end supports with a connecting grid-like supporting member for each flat face of the drum and a foraminous plate secured to said supporting member.

55 30. A rotary screen drum having a foraminous covering and a support therefor comprising end supports and a series of supporting units connecting the same, each unit providing a seat to which opposite edges of 60 the foraminous covering is applied and also presenting interiorly arranged, stock-lifting blades.

31. A rotary screen drum having a foraminous covering and a support therefor 65 formed of sectional segments, each segment

comprising a supporting member for the foraminous cover and presenting subdividing partition walls for the interior of the drum.

32. A screening apparatus for paper stock 70 having a rotary screen drum provided with means for screening the stock and lifting and dropping the unscreened residue, means for advancing the unscreened residue between each screening operation and the next, 75 a stock inlet through which stock is delivered to one end of the drum, said inlet having a settling chamber to receive sand and other impurities.

33. A screening apparatus for paper stock 80 having a rotary screen drum provided with means for screening the stock and lifting and dropping the unscreened residue, means for advancing the unscreened residue between each screening operation and the next, 85 a stock inlet through which stock is delivered to one end of the drum, said inlet having a settling chamber to receive sand and other impurities and having also a cleaning opening for said settling chamber.

34. A screening apparatus for paper stock having a rotary screen drum, stock inlet means and a settling chamber for said stock inlet means adapted to receive sand and other impurities.

35. A screening apparatus for paper stock having a rotary screen drum, stock inlet means and a settling chamber for said stock inlet means adapted to receive sand and other impurities, said chamber having a 100 cleaning opening.

36. A screening apparatus for paper stock, the same having a rotary screen drum with means for screening the stock, lifting and dropping the unscreened residue, means for advancing the stock after each screening operation, means for diluting the stock between each screening operation and the next, a tailings delivery outlet and means for thickening the tailings.

37. A screening apparatus for paper stock, the same having a rotary screen drum with means for screening the stock, lifting and dropping the unscreened residue, means for advancing the stock after each screening operation, means for diluting the stock between each screening operation and the next, a tailings delivery outlet, a tailings drying device and means for diverting the tailings at will to said drying device.

38. A pulp screen for screening paper stock in stages comprising a screen drum having stock-lifting walls and means for rotating the drum whereby the stock is screened and the unscreened residue lifted 125 and dropped by said lifting walls, means for diluting the thickened residue, devices to receive the discharged residue and divert and deliver it to said drum at a more advanced point therein for a repetition of the 130

screening action, and a draining drum to receive the tailings, outside of the action of said diluting means, whereby the consistency of said tailings may be thickened.

5 39. A pulp screen for screening paper stock in stages comprising a screen drum having stock-lifting walls and means for rotating the drum whereby the stock is screened and the unscreened residue lifted and dropped by said lifting walls, means for diluting the thickened residue, devices to receive the discharged residue and divert and deliver it to said drum at a more advanced point therein for a repetition of the 10 screening action, and drying means for thickening the tailings.

40. A pulp screen for screening paper stock in stages comprising a screen drum having stock-lifting walls and means for 20 rotating the drum whereby the stock is screened and the unscreened residue lifted and dropped by said lifting walls, means for diluting the thickened residue, devices to receive the discharged residue and divert 25 and deliver it to said drum at a more advanced point therein for a repetition of the screening action, drying means for thickening the tailings and means for discharging the tailings at will with or without the action 30 thereon of said drying means.

41. A screening apparatus for paper stock, the same having a rotary screen drum, a casing therefor, means whereby stock may be screened by said drum and the residue lifted and dropped, feeding means for advancing the unscreened residue and delivering it again to the drum, and one or more removable closures in said casing to permit access to the interior of the drum.

40 42. A screening apparatus for paper stock, the same having a rotary screen drum, a casing therefor, means whereby said drum is adapted to screen the stock and lift and drop the unscreened residue, a stock repository for taking the unscreened residue and redelivering it to the drum at a more advanced point, the same comprising a stationary feed member having diagonally arranged feed passages therein, and one or 45 more removable closures for said casing to provide access to said feed member.

43. A screening apparatus for paper stock, the same comprising a rotary screen drum, a casing therefor and means for feeding stock to the interior of said drum, said casing and said drum having cooperating overflow openings to permit the overflow of said stock in the event of the stoppage of 50 said drum.

60 44. A screen drum having a foraminous covering, a support therefor presenting a seat on which the covering rests and means for securing said foraminous covering to the support, the same including a clamping

device with a clamping face beveled or inclined with relation to the seat.

45. A screen drum having a polygonal cross-section and a foraminous cover composed of flat foraminous plates, an underlying support and means presenting a seat 70 on which the covering rests for securing the plates to said support, the same including a beveled strip overlying the edge of the plate and one or more clamping devices engaging said strip, the clamping faces of said strip and device being inclined or beveled with relation to the seat.

46. A screen drum having a polygonal cross-section and a foraminous covering composed of a plurality of flat foraminous plates, and means for securing the plates to an underlying support including beveled strips overlying the edges of adjacent plates and wedge-shaped clamps engaging the edges of the strips and adapted to be 80 clamped together to hold said plates in position.

47. A screen drum, polygonal in cross-section and having a foraminous covering composed of flat foraminous plates and 90 means for fastening the edges of said plates to an underlying seat or support for the same comprising a clamping device and an intermediate member interposed between the clamping device and the face of the 95 plate, said members having cooperating engaging faces inclined at an angle to the seat on which the plate rests.

48. The combination with a screen having a tailings outlet of a drying device comprising a rotary draining drum adapted to receive said tailings on its inner surface and drain the water therefrom, said drum having 100 separate discharge passages for the water and the thickened tailings.

49. The combination with a screen having means for screening paper stock and for diluting and rescreening the unscreened residue of a drying device comprising a rotary draining drum adapted to receive the tailings on its inner surface and drain the water therefrom and having separate discharge 110 passages for the water and the thickened tailings.

50. The process of working paper stock 115 which consists in screening the stock, diluting and rescreening the residue, withdrawing the final tailings and thickening them by withdrawing the moisture therefrom.

51. In a structure of the class described, 120 the combination of a foraminated cylinder, a series of internal dippers adapted to elevate and discharge the stock as the cylinder rotates, a series of compartments into which the stock is discharged from said dippers, 125 said dippers and compartments coacting to advance the stock through the cylinder, and sprays directed across the path of the

stock between its discharge from the dippers and return to the cylinder.

52. In a structure of the class described, the combination of a foraminated cylinder, a series of internal dippers adapted to elevate and discharge the stock as the cylinder rotates, a series of compartments into which the stock is discharged from said dippers,

said dippers and compartments coacting to advance the stock through the cylinder, and means for agitating the stock within the compartments.

In testimony whereof, I have signed my name to this specification.

ANTON J. HAUG.
